(57) **CLAIM**

The ornamental design for a meter box grounding clamp, as shown and described herein.

DESCRIPTION

FIG. 1 is an isometric view of a meter box grounding clamp according to my new design.

FIG. 2 is another isometric view of the meter box grounding clamp of FIG. 1 including a meter box in phantom.

FIG. 3 is a front view of the meter box grounding clamp of FIG. 1.

FIG. 4 is a back view of the meter box grounding clamp of FIG. 1.

FIG. 5 is a right view of the meter box grounding clamp of FIG. 1.

FIG. 6 is a left view of the meter box grounding clamp of FIG. 1.

FIG. 7 is a top view of the meter box grounding clamp of FIG. 1; and,

FIG. 8 is a bottom view of the meter box grounding clamp of FIG. 1.

The broken lines showing environment form no part of the claimed design.
